MAGNETICALLY ACTUATED PUMP

Melmoth W. Hunter, Lorain, Ohio

Application July 22, 1957, Serial No. 673,285

21 Claims. (Cl. 103—118)

This invention relates to pumps, and in particular relates to a magnetically actuated pump for pumping fluids.

The present invention is an improvement over prior Melmoth W. Hunter patents, Nos. 2,033,577 and 2,788,747.

One object of the present invention is to provide an improved magnetic pump unit which is separably attached to a pump housing, as in the aforesaid Patent No. 2,788,747, but wherein improved means is provided for quickly detachably securing the pump unit on the housing in any one of an infinite number of rotatably adjusted positions, through 360 degrees, with respect to a longitudinal axis of the pump, and thereby making it possible to mount the pump unit on the housing with an outlet conduit or like protrusion extending radially therefrom to avoid obstructions near the pump.

Another object of the invention is to provide a pump unit of the character described having a revolving magnetic attraction device in the housing, utilized in known manner for tipping a wobbler disc within the pump chamber in continuous circumferential progression, including improved magnetic circuit means from said magnetic attraction device through said pump unit and wobbler disc, and by which loss of magnetic flux in the system is reduced to a minimum.

Another object of the invention is to provide a pump unit of the character described having improved means for self-centeringly mounting the wobbler disc therein for said continuous tipping action of the disc, said self-centering means being such that the disc is reversible and hence may be mounted in the pump chamber with either side presented inwardly thereof, toward said magnetic attraction device.

Another object of the invention is to provide a pump of the character described having improved magnetic attraction means, including a rotor extension provided with counter-balanced portions of magnetic and non-magnetic materials, and presenting a solid body through an opening in the wall of the housing, toward cooperation with the pump unit, without protrusions which could cause injury while the pump is being cleaned or repaired, and which makes possible the provision of an effective fluid seal between said solid body and the edge portions of the opening through which it extends, which in turn prevents passage of oil, dirt, or foreign matter in either direction through said housing opening.

Another object of the invention is to provide a pump unit of the character described, including between said rotor extension or body and said disc a relatively thin wall or diaphragm having the characteristic of passing magnetic flux therethrough, and wherein improved means is provided for supporting said thin wall against fluid pressure produced within the pump which might otherwise deform the wall, whereby is made possible the production of pumps of substantially unlimited capacity, without necessarily increasing the thickness of said thin wall.

2

Another object of the invention is to provide improvements in wobbler discs for pumps of the character described, which eliminate or effectively reduce eddy currents in the magnetic flux passed through the discs which otherwise would produce electrical currents capable of counteracting the established magnetic field in the pump-actuating system.

These and other objects of the invention will be manifest from the following brief description and the accompanying drawings.

Of the accompanying drawings:

Figure 1 is a top plan view of a magnetic pump embodying the features of the invention.

Figure 2 is an end elevation thereof, as viewed from the right of Figure 1.

Figure 3 is an enlarged fragmentary vertical cross-section of the pump, taken substantially on the line 3—3 of Figure 1.

Figure 4 is an end view of the pump unit casing in the relative position shown in Figure 2, but removed from the pump housing, and with an end closure cap and wobbler disc removed from the casing.

Figure 5 is a vertical cross-section taken substantially on the line 5—5 of Figure 3, but on a reduced scale, and illustrating the interior of the pump chamber with the wobbler disc removed.

Figure 6 is a similar vertical cross-section, taken substantially on the line 6—6 of Figure 3, but with the pump unit removed to show an exposed end of a magnetic rotor extension, and illustrating improved sealing means provided between the same and an opening to the pump housing.

Figure 7 is a view corresponding to Figure 3, illustrating a modified form of magnetic pump, including improved means for self-centeringly mounting the wobbler disc in the pump chamber by which the wobbler disc is reversible without affecting the self-centering operation of the same.

Figure 8 is an edge view, partly broken away, and in section, of the wobbler disc illustrated in Figures 3 and 7, but in greater detail to illustrate means for preventing the creation of eddy currents magnetic flux within the wobbler disc during operation of the pump.

Figure 9 is an edge view corresponding to Figure 8 illustrating another structure for eliminating said eddy currents.

Figure 10 is a view substantially corresponding to Figures 8 and 9, but illustrating still another form of disc designed to obviate creation of eddy currents.

Figure 11 is a top plan view, partly broken in section, of the wobbler disc shown in Figure 10.

Figure 12 is a fragmentary cross-section of still another modified form of the invention, which is in part like that shown in Figure 9.

Figure 13 is a fragmentary cross-section, corresponding to a portion of Figure 3, illustrating another modified form of the invention particularly relating to the pump unit.

Figure 14 is a plan view of the wobbler disc shown in Figure 13, but removed from the pump unit.

GENERAL DESCRIPTION

Referring particularly to Figures 1 to 6, the numeral 15 designates generally a magnetic pump, including an electric motor 16 mounted on a supporting base 17; a magnetic attraction unit 18, suitably removably attached to the motor 16; and a magnetic pump unit 20 removably mounted on magnetic attraction unit 18 in a manner and for purposes to be described, as by means of a clamping mechanism 21.

Magnetic attraction unit

The magnetic attraction unit 18 includes a cylindrical hollow housing 22 removably secured on the motor 16 (see Figure 3), and having peripheral, inner, and outer walls 23, 24 and 25, respectively, said housing having therein an elongated rotor sleeve 26 of magnetic material which is affixed or keyed on an extension 27 of a driven shaft 28 of motor 16, to rotate therewith about a longitudinal axis of the pump. Also, within the housing 22 may be affixed an annular magnetic coil 29 of known type adapted, when energized, to set up a magnetic field through rotor sleeve 26, and otherwise in a manner to be described later.

On the outer end of sleeve 26 axially thereof may be a solid disc-like head or enlarged body 30, which is a composite of two segments made of magnetic and non-magnetic materials respectively, integrally united in known manner, said rotor head having an axially, outwardly presented annular surface portion 31, defining a frustum of a cone. The peripheral edge 32 of the rotor head 30 may be cylindrical, as for fluid and dirt sealing frictional engagement with an annular gasket 33 of rubber-like resilient material, cemented or otherwise affixed within an opening 34 in housing wall 25, through which opening a portion of the rotor head 30 protrudes to have at least said annular conical surface 31 free and unobstructed, as shown in Figure 3.

A magnetic portion 35 of the rotor head 30 constitutes a relatively small segment thereof, and may be an integral angular extension of the magnetic material of sleeve 26, said extension or segment 35 terminating in a substantial surface area, indicated at 36 in Figure 6, which is radially offset with respect to the axis of the rotor shaft 27. The non-magnetic segment 37 of the rotor head, together with integral non-magnetic extensions 38 thereof surrounding segment 35, counter-balance the head somewhat in the manner of a flywheel for smooth rotation of the rotor by motor 16.

It should be noted that when the pump unit 20 is removed from the rotor housing 22, as shown in Figure 6, only smooth surface portions of rotor head 30 are exposed, rather than protruding parts which might prove dangerous while rotating.

Magnetic pump unit

Pump unit 20 may include a hollow casing 19 having a one-piece cup-shaped body 39 of relatively non-magnetic material, including a cylindrical peripheral wall 40 and a relatively thin, outwardly dished inner wall or diaphragm 41, which presents an annular conical surface 42, of the inner or concave side thereof, in slightly spaced relation to the conical annular face 31 of rotor head 30, whereby as the rotor head is rotated by motor 16 the exposed magnetized surface area 36 will move in a circular orbit about the axis of the rotor, for purposes to be described. A cap 44 of magnetic material, constituting an outer wall of the pump unit casing 19, may have a reduced inner portion 45 tightly received within the inner surface of peripheral wall 40 defining an annular seat 50, for fluid-retaining engagement with the outer edge of wall 40. The cup-shaped body 39 may have the peripheral wall 40 thereof suitably bonded, as by soldering or brazing methods, within a cylindrical sleeve 46, of magnetic material, said sleeve being extended at 48 beyond the inner edge of peripheral wall 40 for seating in an annular seat 49 in wall 25 of the rotor housing. The outer end of sleeve 46 terminates in a welded extension connecting the same to peripheral wall 40, and a gasket 51 of rubber or the like provides a fluid seal between the flush edges of peripheral walls 40 and 46 and seat 50.

The reduced portion 45 of cap 44 may have an inwardly convergent frusto-conical surface portion 53 which is axially spaced from the oppositely disposed, outwardly convergent frusto-conical surface portion 54 of the diaphragm 41. At least portions of conical portions

53 and 54 are simultaneously engageable by diametral-
ly and axially opposite flat sides of a relatively thin flat-
sided wobbler disc 55 of magnetic material, which will be
described in detail later (see Figure 3). The wobbler
disc 55 is of a diameter only slightly less than the inner
peripheral surface 56 of the peripheral wall 40, whereby
in all positions of the wobbler disc during operation of
pump in a manner which will be described later, the
peripheral edge 57 of the disc will be in substantially
close conformity with said peripheral wall surface 56, and
cannot fall substantially out of axial operational alignment
within the pump chamber C. Thus, the wobbler
disc will at all times during operation of the pump
divide the pump chamber C into two substantially dis-
tinct wedge-shaped pockets at opposite sides of the disc,
which communicate with each other substantially only
through a central opening 58 of substantial flow area
through the disc, to be in substantial alignment with an
inlet opening 59 of substantially the same or correspond-
ing flow area through the cap. The opening 59 extends
axially through a reduced neck 60 to which may be
threaded a suitable coupling device on a conduit (see
chain-dotted lines in Figure 3) from a gravity feed or
other source of liquid supply, such as milk, oil, sea
water, etc. A neck 61 extending radially outwardly from
the peripheral wall 40 and through an opening in the
sleeve 46, has an outlet opening 62 therethrough from the
pump chamber C, the outer end of the neck 61 being
threaded for coupling attachment of a conduit (see chain-
dotted lines in Figure 3).

The aforementioned Patent No. 2,788,747 shows means for self-centering the wobbler disc at all times during operation of the pump. The means referred to in the patent, however, required provision of protruding guide means on one side of the disc, so that it was possible for the disc to be inserted within the pump chamber with a wrong side presented to complementary guide means on the magnetic diaphragm, thereby to result in improper or inefficient operation of the pump. This difficulty is obviated in the present instance by provision of a disc 55 which has identical flat sides, and of a flat boss 63 of shallow depth on diaphragm 41, within the pump chamber, the diameter of the boss approximating the diameter of the opening 58 in the disc. The boss 63 defines a filleted peripheral shoulder 64 for complementary reception of either corner edge portion 65 defined by said central opening of the disc, at points of progressive contact thereof, as best shown in Figure 3. In any event, the progressive contact of the corner portions 65 of the disc with shoulder portion 64 is effective to retain the wobbler disc in self-centered relation during operation of the pump to impart requisite progressive wave-like tilting movement to the disc.

As will be best understood by reference to Figure 3, frictional contact between the opposite engaging portions of the disc with the corresponding conical portions of the diaphragm and the cap will be reduced to a minimum if the adjacent surface portions diverge radially outwardly to a slight degree from the respective progressive points of contact.

In case it is desired to produce pumps of substantially large capacity without substantially increasing the thickness of the diaphragm 41, a suitable frictional thrust bearing 72 may be provided between the end of rotor head 30 and the central portion of the diaphragm.

Pump unit attaching means

The pump unit attaching means 21 may comprise an elongated bar 67 having a central opening 68, through which the neck 60 of cap 44 may pass freely, the opposite ends of the bar having oppositely disposed open-ended notches or slots 69, for quick reception of clamping rods 70 fixedly mounted in the outer wall 25 of the rotor housing to extend axially outwardly thereof. Thus, in Figures 1 and 2, the bar 67 has been turned in counter-

clockwise direction (Figure 2), to engage the rods 70 in the notches 69. A pair of nuts 71 threaded on the outer ends of rods 70 are operable against the ends of the bar 67 to apply clamping action to the cap 44, and thereby to clamp the pump unit in the seat portion 49 of wall 25 of the rotor housing, with all parts of the pump casing 39 assembled in fluid-sealing relationship. When it is desired to remove the pump unit 20 from rotor housing 22, as for cleaning purposes, it is only necessary to loosen the nuts 71 and turn the bar 67 in clockwise direction, as shown in Figure 2, to disengage the ends of the bar from the rods 70, whereby the bar is removable from the neck 60 of the cap 44 to release the pump casing from seating position in the seat 49.

The clamping bar 67, rods 70, and housing 22 are of magnetic metal. Accordingly, in operation of the pump, the magnetic flux field or circuit from the coil 29 will be in the direction of the small arrows shown in Figure 3, namely, through rotor 26, rotor extension 35, diaphragm 54, wobbler disc 55, cap 44, clamping bar 67, clamping rods 70, and the housing walls back to coil 29. Thus, because the pump casing sleeve 49 is of non-magnetic material, the magnetic flux will not short to the sleeve 46 from the outermost edge portions of the disc relatively as shown in Figure 3, which would tend to reduce the efficiency of the pump.

Wobbler disc

The wobbler disc 55 may be made substantially as shown in Figure 8, or in the manner of modifications thereof shown in Figures 9 to 12, to eliminate or substantially reduce the tendency for eddy currents of magnetic flux to form within the body of the disc during operation of the pump, which eddy currents tend to create electrical current which would otherwise offset or interfere with the flow of magnetic flux in the circuit thereof through the magnetic coil 29.

Figure 8 shows the disc 55 as being formed of a thin walled hollow casing of magnetic metal, filled with discrete pieces or particles of metal, such as iron or steel shavings, granules, or powder, insulated from each other by dielectric material, such as lacquer, latex plastic, enamel, baked or otherwise hardened into a solid agglomerate mass.

Figure 9 illustrates a modified form of wobbler disc 55a which is of the same shape and proportions as disc 55 but formed of laminations 74—74 of magnetic metal, secured together as by means of rivets 73, said laminations being similarly insulated from each other, as by means of thin layers of shellac.

Figures 10 and 11 illustrate still another modified form of wobbler disc 55b, which is in all respects like the disc 55 shown in Figure 8, except that the hollow casing 65a is filled with a spirally wound tape of thin magnetic metal as indicated at 74b, adjacent surfaces of the tape and the inner surfaces of the casing being insulated from each other, as before.

Figure 12 illustrates still another modified form of wobbler disc 55c, which is in all respects like the disc 55 of Figure 8, but with thin insulated laminations 74a—74a of magnetic material as in Figure 9, encased in a hollow casing of magnetic material.

Operation of pump

In operation of the improved pump, as shown in Figures 1 to 6, as for pumping milk fed by gravity to pump chamber C, motor 16 is operated for continuous rotation of the rotor 26 and rotor head 30, to move the terminal end 36 of the magnetic rotor extension 35 continuously and steadily, and at a substantially high rate of speed, in a circumferential path or orbit offset with respect to the axis of the pump. Magnetic attraction of the wobbler disc to the diaphragm 41, and to said revolving magnetic rotor extension or segment 35, imparts to the disc a circumferentially progressively tilting

movement without substantial rotation of disc, the disc being maintained at the same relative inclination to the axis of the pump by engagement of axially and diagonally opposite sides of the disc with corresponding axially and diagonally opposite conical guide surface portions 54 and 53 of the diaphragm and cap, 41 and 44, respectively. During resultant progressive wave-like tilting of the disc, as described, it is maintained in centered relation, with its central opening 58 in alignment with inlet opening 59 in the cap, by circumferentially progressive point contact or engagement of the inner annular corner edge 65 of the disc with the peripheral shoulder 64 on the diaphragm. In this way, the disc is continuously maintained in said axially centered relation with a minimum of frictional contact with the conical guide surfaces, and without pivot pins or other obstructions at the center of the disc. Accordingly, milk enters the pump chamber C through inlet opening 59 in cap 44, and fills wedge-shaped pockets at diagonally and axially opposite sides of the disc (see Figure 3) and is continuously moved by circumferentially progressive tilting action of the disc toward the outlet opening 62 in the pump casing, thereby to be conveyed under substantial pressure induced in the pump chamber C to a milk treating or other device, such as a cream separator.

Because of the substantially unrestricted flow of milk from the inlet 59 to the pockets at both sides of the disc, movement within the pump chamber C toward the outlet opening 62 will be without substantial agitation or turbulence which could have detrimental effect on the quality of the milk. The flywheel-like action of the rotor head 30 obviates chattering or vibration within the pump.

When the motor 16 is stopped after a pumping period of operation, and the magnetic coil is de-energized, the wobbler disc 55 will be de-magnetized and free to fall by gravity into edgewise support on the bottom of peripheral wall 40, as indicated by chain-dotted lines in Figure 3. That is, the disc 55 will always be freely and unobstructedly supported in a substantially axially centered position for tilting movement in all directions, and there being no pins or other obstructions to interfere with subsequent self-centering movement of the disc and progressive tilting action of the same, as when the pump is again operated as described. That is, upon subsequent rotation of the rotor head 30, the disc 55 will again be attracted to a self-centered, inclined position for continuous progressive tilting movement of the same.

Modified pump units

Referring to Figure 7, there is illustrated a modified form of pump unit 76 clamped in seated relation on a rotor unit 18a which is in all respects like the rotor unit 18 described in connection with Figures 1 to 6, like parts thereof being designated by like numerals. The pump unit 76 is substantially similar to the pump unit 20 of Figures 1 to 6, except that it includes a modified form of self-centering means for the disc 55. Accordingly, again like parts will be given like numerals unless otherwise designated.

In the operational condition of the pump, the disc 55 is drawn toward the frusto-conical surface 54a of diaphragm 41a, and into the tilting position shown by the full lines in Figure 7, as from the chain-dotted line position. Thus the disc is drawn into a tilted position in which a marginal corner edge at the outer periphery thereof is complementally seated in substantial point contact with an annular filleted seat 77 defined at the juncture of said frusto-conical face 54a and a radially arcuate inner peripheral surface 78 of inner pump wall 40a. When the rotor head 30 is continuously rotated as before, magnetic extension 35 moving in a circular orbit will cause circumferentially progressive tilting of the disc 55 while it is continuously maintained in self-centered relation with respect to the axis of the pump.

Figures 13 and 14 illustrate another modified form of pump unit 20a utilizing a magnetically attractive wobbler disc 55 of one or other of the types shown in Figures 8 to 12, but wherein a disc 55d is provided with a substantially thick outer marginal portion 55e of non-magnetic metallic or rubber-like material. Accordingly, during operation of the pump as previously described, particularly in connection with Figures 1 to 6, the non-magnetic portion 55e of the disc acts as a barrier or insulator to prevent short circuiting of magnetic flux from the outer edge of the disc to the peripheral wall 39a of the casing, which is of magnetic material. This makes it possible to obviate provision of a non-magnetic insulating sleeve part, corresponding to peripheral wall 40 in Figure 3, so that the path of the magnetic flux from the rotating magnetic extension 35a will be through disc part 55d, cap 44, peripheral wall 39a, and back to the coil 29a through the walls of the magnetic attraction unit 18a.

By this provision of a single peripheral wall 39a on the pump casing, certain major parts of the pump generally may be reduced in size, with a corresponding reduction in cost of manufacturing the pump.

Throughout the foregoing description, reference has been made to magnetic and non-magnetic materials. This means, generally, magnetic material, such as a certain type of stainless material which is highly pervious to passage of magnetic flux, and non-magnetic material, such as another type of stainless steel, which is relatively impervious to passage of flux, and serves substantially as an insulating means. It has been found, moreover, that while the inner walls of the pump casings, referred to herein as the diaphragms, may be of magnetic metal, the improved pump will operate more efficiently if the diaphragms are of non-magnetic metal, the only requirement being that the material be of such character as to permit passage of flux therethrough, which almost any material will do. As an example, flux from a common small magnet will attract metal through paper.

Conclusion

In all forms of the present invention, the pump unit is completely sealed against entry of foreign matter to the pump chamber C from any source whatsoever. The pump unit may be easily removed from the rotor housing 18 by releasing the nuts 71, turning the bar 67 in clockwise direction to be free of the nuts and the rods 70, and removing the bar outwardly of the neck 60 of cap 44. This permits rapid removal of the pump casing from seating position in seat 49 of the rotor housing, after which the cap 44 is readily removed from the pump body 39 for access to the interior of the pump chamber and removal of the wobbler disc 55, as for cleaning the various parts. Conversely after these parts have been thoroughly cleaned, they are just as readily assembled in the liquid-sealed, operative positions thereof previously described, by means of the quick-operating clamping device 21.

Further modifications of the invention may be resorted to without departing from the spirit thereof or the scope of the appended claims.

What is claimed is:

1. The combination with a magnetic pump or like device including a casing having walls defining a pump chamber and revolving magnetic attraction means, a magnetically attractive wobbler element mounted in said chamber for continuous circumferential tipping movement by said revolving magnetic attraction means, said wobbler element comprising a body formed of closely arranged portions of magnetically attractive material, adjacent said portions being generally electrically insulated from each other to minimize eddy currents by magnetic flux passed through the body.

2. The combination as set forth in claim 1, wherein said magnetically attractive material is laminated magnetic metal.

3. The combination as set forth in claim 1, where

said magnetic material is strip metal arranged in a spiral thereof.

4. The combination as set forth in claim 1, wherein said magnetic material is strip metal arranged in a spiral thereof, said spiral metal being contained in a casing of magnetically attractive material.

5. The combination with a magnetic pump including a casing having walls defining a pump chamber and revolving magnetic attraction means, a magnetically attractive wobbler element mounted in said chamber for continuous circumferential tipping movement by said revolving magnetic attraction means, said wobbler element comprising a body formed of closely arranged portions of magnetically attractive material, adjacent said portions being generally electrically insulated from each other to minimize eddy currents by magnetic flux passed through the body, said portions being a plurality of axially superposed sheets of magnetic metal.

6. The combination with a magnetic pump including
20 a casing having walls defining a pump chamber and re-
volving magnetic attraction means, a magnetically attrac-
tive wobbler element mounted in said chamber for con-
tinuous circumferential tipping movement by said re-
volving magnetic attraction means, said wobbler element
25 comprising a body formed of closely arranged portions
of magnetically attractive material, adjacent said por-
tions being generally electrically insulated from each
other to minimize eddy currents by magnetic flux passed
through the body, said body being contained in hollow
30 casing of relatively magnetically attractive material, and
said portions of the body being an agglomerate of pieces
of magnetic metal and an insulating material separating
the pieces.

7. The combination with a magnetic pump including
35 a casing having walls defining a pump chamber and re-
volving magnetic attraction means, a magnetically attrac-
tive wobbler element mounted in said chamber for con-
tinuous circumferential tipping movement by said revol-
ving magnetic attraction means, said wobbler element com-
40 prising a body formed of closely arranged portions of
magnetically attractive material, adjacent said portions
being generally electrically insulated from each other to
minimize eddy currents by magnetic flux passed through
the body, means providing a circuit for magnetic flux
from said magnetic attraction means through said disc and
45 exteriorly of said casing back to said magnetic attraction
means.

- means.

8. A magnetic pump, comprising a casing having walls therein defining a fluid-pump chamber, a relatively thin inner wall of said casing being of material having the property of passing magnetic flux therethrough and having a generally conical portion dished inwardly of said chamber, a wobbler element mounted in said chamber, a rotor having a magnetically energizable core rotatable on an axis through the center line of said conical portion, said core having a generally circular body encased thereon, said body being a composite of magnetic and non-magnetic materials, the magnetic portion of said body being in magnetic conductivity with said core and terminating in a surface portion complementary to said generally conical portion at the concave side thereof and in spaced relation thereto, said terminal surface portion thereby being generally offset with respect to said axis, and means for rotating said rotor whereby through magnetic attraction of said wobbler element to the rotating magnetic extension the wobbler element is continuously tipped at an inclination to said axis of said rotor in circumferential progression.

9. A magnetic pump as set forth in claim 8, including a support for said casing having a peripheral opening through which said body extends, the edge of said peripheral opening being spaced with respect to the outer periphery of said body, means being provided for fluid sealing said space.

n 75 10. A magnetic pump as set forth in claim 8, wherein

said body has a generally conical portion complementary to said conical portion of said inner wall and in spaced relation thereto.

11. A magnetic pump, comprising a casing having peripheral and inner and outer walls defining a fluid-pumping chamber having an axis therethrough, said inner wall being relatively thin and being of material having the characteristic of passing magnetic flux therethrough and said outer wall being in axially spaced relation to said inner wall, a magnetically attractive wobbler disc having central opening means of substantial flow area through the same, inlet and outlet means in said casing for passage of fluid through said chamber, said inner and outer walls having inwardly oppositely converging, generally conical surface portions, and rotatable magnetic attraction means presented exteriorly of said chamber and terminating adjacent said inner end wall at a point offset with respect to said axis to move in a continuous orbit co-extensive with said conical surface portion of the inner wall, progressively to attract said disc toward the inner wall and to tilt the disc toward engagement of opposite sides thereof with said opposite conical surface portions, whereby through continued rotation of said magnetic attraction means in said orbit said disc is continuously tipped at an inclination to said axis in circumferential progression, said disc having an annular shoulder of substantially right-angular cross section and said casing having an annular seat of substantially complementary right-angular cross-section for complementally receiving the annular shoulder at the points of circumferentially progressive contact therewith.

12. A magnetic pump, comprising a casing having peripheral and inner and outer walls defining a fluid-pumping chamber having an axis therethrough, said inner wall being relatively thin and being of material having the characteristic of passing magnetic flux therethrough and said outer wall being in axially spaced relation to said inner wall, a magnetically attractive wobbler disc having central opening means of substantial flow area through the same, inlet and outlet means in said casing for passage of fluid through said chamber, said inner and outer walls having inwardly oppositely converging, generally conical surface portions, and rotatable magnetic attraction means presented exteriorly of said chamber and terminating adjacent said inner end wall at a point offset with respect to said axis to move in a continuous orbit co-extensive with said conical surface portion of the inner wall, progressively to attract said disc toward the inner wall and to tilt the disc toward engagement of opposite sides thereof with said opposite conical surface portions, whereby through continued rotation of said magnetic attraction means in said orbit said disc is continuously tipped at an inclination to said axis in circumferential progression, an annular seat being provided centrally on said inner wall and said disc having an annular shoulder defined by an edge portion of said central opening means, said seat complementally receiving said annular shoulder at points of circumferentially progressive contact therewith.

13. A magnetic pump, comprising a casing having peripheral and inner and outer walls defining a fluid-pumping chamber having an axis therethrough, said inner wall being relatively thin and being of material having the characteristic of passing magnetic flux therethrough and said outer wall being in axially spaced relation to said inner wall, a magnetically attractive wobbler disc having central opening means of substantial flow area through the same, inlet and outlet means in said casing for passage of fluid through said chamber, said inner and outer walls having inwardly oppositely converging, generally conical surface portions, and rotatable magnetic attraction means presented exteriorly of said chamber and terminating adjacent said inner end wall at a point offset with respect to said axis to move in a continuous orbit co-extensive with said conical surface portion of the

inner wall, progressively to attract said disc toward the inner wall and to tilt the disc toward engagement of opposite sides thereof with said opposite conical surface portions, whereby through continued rotation of said magnetic attraction means in said orbit said disc is continuously tipped at an inclination to said axis in circumferential progression, an annular seat being provided at the juncture of said inner wall and said peripheral wall, and said disc having an outer peripheral edge complementally engageable in said seat and contacting said peripheral wall at said seat at points of circumferentially progressive contact therewith.

14. A magnetic pump, comprising a casing having peripheral and inner and outer walls defining a fluid-pumping chamber having an axis therethrough, said inner wall being relatively thin and being of material having the characteristic of passing magnetic flux therethrough and said outer wall being in axially spaced relation to said inner wall, a magnetically attractive wobbler disc having central opening means of substantial flow area through the same, inlet and outlet means in said casing for passage of fluid through said chamber, said inner and outer walls having inwardly oppositely converging, generally conical surface portions, and rotatable magnetic attraction means presented exteriorly of said chamber and terminating adjacent said inner end wall at a point offset with respect to said axis to move in a continuous orbit co-extensive with said conical surface portion of the inner wall, progressively to attract said disc toward the inner wall and to tilt the disc toward engagement of opposite sides thereof with said opposite conical surface portions, whereby through continued rotation of said magnetic attraction means in said orbit said disc is continuously tipped at an inclination to said axis in circumferential progression, said disc having an annular shoulder and said casing having an annular seat for complementally receiving the annular shoulder at points of circumferentially progressive contact therewith, said magnetic attraction means including a rotatable member and bearing means being mounted between said member and said inner wall to support the same against opposing pressure of the disc.

15. A magnetic pump, comprising a casing having peripheral and inner and outer walls defining a fluid-pumping chamber having an axis therethrough, said inner wall being relatively thin and being of material having the characteristic of passing magnetic flux therethrough and said outer wall being in axially spaced relation to said inner wall, a magnetically attractive wobbler disc having central opening means of substantial flow area through the same, inlet and outlet means in said casing for passage of fluid through said chamber, said inner and outer walls having inwardly oppositely converging, generally conical surface portions, and rotatable magnetic attraction means presented exteriorly of said chamber and terminating adjacent said inner end wall at a point offset with respect to said axis to move in a continuous orbit co-extensive with said conical surface portion of the inner wall, progressively to attract said disc toward the inner wall and to tilt the disc toward engagement of opposite sides thereof with said opposite conical surface portions, whereby through continued rotation of said magnetic attraction means in said orbit said disc is continuously tipped at an inclination to said axis in circumferential progression, an annular seat being provided at the juncture of said inner wall and said peripheral wall, and said disc having an outer peripheral edge complementally engageable in said seat and contacting said peripheral wall at said seat at points of circumferentially progressive contact therewith, said magnetic attraction means including a rotatable member and bearing means being mounted between said member and said inner wall to support the same against opposing pressure of the disc.

16. A magnetic pump, comprising a housing having an opening therein and seat means around said opening, a

casing having peripheral and inner and outer walls defining a fluid-pumping chamber having an axis therethrough, said casing having seat portions seating against said seat means, said inner wall being relatively thin and being of material having the characteristic of passing magnetic flux therethrough and said outer wall being in axially spaced relation to said inner wall, a magnetically attractive wobbler disc mounted in said chamber to have tilting movement in all directions angularly of said axis, rotatable magnetic attraction means presented exteriorly of said chamber and terminating adjacent said inner wall at a point offset with respect to said axis to move in a continuous orbit about the same, progressively to attract said disc toward the inner wall and to tilt the disc whereby it is continuously tipped at an inclination to said axis in circumferential progression, peripherally spaced elements on said housing to extend outwardly of said casing, a clamping bar mounted between said spaced elements, and adjustable means on said elements operable against said bar to clamp said casing into seating engagement of said seat portions thereof with said seat means, the spaces between said elements radially outwardly of said peripheral wall of the casing being free and unobstructed, said casing having a conduit or like radial extension from said peripheral wall in said free and unobstructed spaces in one of various selective positions of rotational adjustment of the casing in said seat means.

17. A magnetic pump, comprising a housing having an opening therein and seat means around said opening, a casing having peripheral and inner and outer walls defining a fluid-pumping chamber having an axis therethrough, said casing having seat portions seating against said seat means, said inner wall being relatively thin and being of material having the characteristic of passing magnetic flux therethrough and said outer wall being in axially spaced relation to said inner wall, a magnetically attractive wobbler disc mounted in said chamber to have tilting movement in all directions angularly of said axis, rotatable magnetic attraction means presented exteriorly of said chamber and terminating adjacent said inner wall at a point offset with respect to said axis to move in a continuous orbit about the same, progressively to attract said disc toward the inner wall and to tilt the disc whereby it is continuously tipped at an inclination to said axis in circumferential progression, peripherally spaced elements on said housing to extend outwardly of said casing, a clamping bar mounted between said spaced elements, and adjustable means on said elements operable against said bar to clamp said casing into seating engagement of said seat portions thereof with said seat means, the spaces between said elements radially outwardly of said peripheral wall of the casing being free and unobstructed, said casing having a conduit or like radial extension from said peripheral wall in said free and unobstructed spaces in one of various selective positions of rotational adjustment of the casing in said seat means, said outer wall of the casing including a cap removably seated in sealed relation on said peripheral wall, said clamping bar having portions engaging said cap to hold the same seated in said sealed relation.

18. A magnetic pump, comprising a housing having an opening therein and seat means around said opening, a casing having peripheral and inner and outer walls defining a fluid-pumping chamber having an axis therethrough, said casing having seat portions seating against said seat means, said inner wall being relatively thin and being of material having the characteristic of passing magnetic flux therethrough and said outer wall being in axially spaced relation to said inner wall, a magnetically attractive wobbler disc mounted in said chamber to have tilting movement in all directions angularly of said axis, rotatable magnetic attraction means presented exteriorly of said chamber and terminating adjacent said inner wall at a point offset with respect to said axis to move in a continuous orbit about the same, progressively to attract said

disc toward the inner wall and to tilt the disc whereby it is continuously tipped at an inclination to said axis in circumferential progression, peripherally spaced elements on said housing to extend outwardly of said casing, a clamping bar mounted between said spaced elements, and adjustable means on said elements operable against said bar to clamp said casing into seating engagement of said seat portions thereof with said seat means, the spaces between said elements radially outwardly of said peripheral wall of the casing being free and unobstructed, said outer wall of the casing including a cap removably seated in sealed relation on said peripheral wall, said clamping bar having portions engaging said cap to hold the same seated in said sealed relation, said peripheral wall of the casing being a composite of inner and outer stratas of different materials, the outer said strata being of magnetically attractive material, said cap being of magnetically attractive material and being seated on said inner strata, the inner said strata being of magnetically non-conducting material and being seated on said seat means, the path of magnetic flux being from the magnetic attraction means through said diaphragm, said disc, said cap, and returned through conductor means provided externally of said casing back to the magnetic attraction means.

19. A magnetic pump, comprising a housing having an opening therein and seat means around said opening, a casing having peripheral and inner and outer walls defining a fluid-pumping chamber having an axis therethrough, said casing having seat portions seating against said seat means, said inner wall being relatively thin and being of material having the characteristic of passing magnetic flux therethrough and said outer wall being in axially spaced relation to said inner wall, a magnetically attractive wobbler disc mounted in said chamber to have tilting movement in all directions angularly of said axis, rotatable magnetic attraction means presented exteriorly of said chamber and terminating adjacent said inner wall at a point offset with respect to said axis to move in a continuous orbit about the same, progressively to attract said disc toward the inner wall and to tilt the disc whereby it is continuously tipped at an inclination to said axis in circumferential progression, peripherally spaced elements on said housing to extend outwardly of said casing, a clamping bar mounted between said spaced elements, and adjustable means on said elements operable against said bar to clamp said casing into seating engagement of said seat portions thereof with said seat means, the spaces between said elements radially outwardly of said peripheral wall of the casing being free and unobstructed, said outer wall of the casing including a cap removably seated in sealed relation on said peripheral wall, said clamping bar having portions engaging said cap to hold the same seated in said sealed relation, said peripheral wall of the casing being a composite of inner and outer stratas of different materials, the outer said strata being of magnetically attractive material, said cap being of magnetically attractive material and being seated on said inner strata, the inner said strata being of magnetically non-conducting material and being seated on said seat means, the path of magnetic flux being from the magnetic attraction means through said diaphragm, said disc, said cap, and returned through conductor means provided externally of said casing back to the magnetic attraction means, said conductor means comprising said clamping bar, said elements, and said housing.

20. The combination with a magnetic pump including a casing having walls defining a pump chamber and revolving magnetic attraction means, a magnetically attractive wobbler element mounted in said chamber for continuous circumferential tipping movement by said revolving magnetic attraction means, said wobbler element comprising a disc-like body which is substantially pervious to passage therethrough of magnetic flux from said magnetic attraction means, said body having around the peripheral edge thereof an annular portion of material

which is substantially impervious to passage of magnetic flux.

21. The combination with a magnetic pump including a casing having walls defining a pump chamber and revolving magnetic attraction means, a magnetically attractive wobbler element mounted in said chamber for continuous circumferential tipping movement by said revolving magnetic attraction means, said wobbler element comprising a disc-like body which is substantially pervious to passage therethrough of magnetic flux from said magnetic attraction means, said body having bonded theron a marginal portion of substantial cross-sectional area and of material which is substantially impervious to passage of magnetic flux.
